UNITED STATES PATENT OFFICE.

JOSEPH C. ZUMWALT, OF CLAY CENTER, NEBRASKA.

ATTACHMENT FOR VEHICLES.

1,290,007.

Specification of Letters Patent. Patented Dec. 31, 1918.

Application filed February 19, 1917. Serial No. 149,590.

To all whom it may concern:

Be it known that I, JOSEPH C. ZUMWALT, a citizen of the United States, residing at Clay Center, in the county of Clay and State of Nebraska, have invented certain new and useful Improvements in Attachments for Vehicles; and I do declare the following to be a full, clear, and exact description of the invention, such as will enable others skilled in the art to which it appertains to make and use the same.

This invention relates generally to motor vehicles and more particularly to certain new and useful improvements in safety steering devices for automobiles or other motor cars.

The primary object of the invention is to produce a means for causing the automobile or other vehicle to hold a straight course without the assistance of the driver.

A still further object of the invention is to generally improve upon devices of this character by the provision of an extremely simple, strong, durable and inexpensive construction, and one which will be very efficient and reliable in operation, and well adapted to the purpose for which it is designed.

With these and other objects in view, the invention consists of certain details of construction and the combination and arrangement of parts as will be hereinafter fully described and claimed.

In the accompanying drawings, forming a part of the application, and in which similar reference characters designate like parts throughout the several views,

Figure 1 is a top plan view;

Figs. 2 and 3 are vertical transverse sections on the lines 2-2 and 3-3 of Fig. 1; and

Fig. 4 is a detail horizontal section on the line 4-4 of Fig. 3.

Referring more particularly to the drawings, the numeral 1 designates, as a whole, an anchor member which comprises a substantially flat rectangular base plate 2 having openings in its four corners. This plate 2 is secured in place by U-bolts 3, whose threaded ends 4 extend through the openings in the corners of said plate and are provided with clamping nuts 5. By this construction the two portions of the clamp 1 are adjustably connected with each other in order that they may be brought into ef-

fective engagement with the axles of automobiles or other vehicles of different sizes.

Formed integrally with the upper face of the plate 2 is an upstanding lug 6, having an opening 6' which receives the front end 60 of a longitudinal spring 8, said spring being secured in said opening by a set screw 7.

The spring 8 is preferably in the form of a straight coiled spring, the adjacent convolutions of which contact with each other 65 to form a substantially cylindrical body. The diameter of the spring 8 is substantially equal to the diameter of the opening 6', and when its front end is disposed in the latter it fits comparatively snugly to assist the 70 set screw 7 in firmly anchoring it therein.

The reference numeral 9 designates a second clamp, one of the portions of which is composed of a plate 10 having a boss 11 on one side thereof. The outer side of the 75 boss 11 is of concave configuration and is provided with a plurality of ridges or corrugations 12 which extend longitudinally with respect to the plate 10. On the opposite sides of the boss 11 and extending 80 through the plate 10 are suitable openings through which extend the opposite ends of the U-bolt 13, the latter constituting the other portion of the clamp 9 and having its externally threaded ends provided with 85 clamping nuts 14.

One end of the plate 10 is provided with a ring-shaped guide member or eye 15, the latter being substantially circular in cross section and being adapted to loosely or slidably receive the other end of the spring 8.

In using a device constructed as above described, the clamp 1 is applied to the front axle A of a vehicle such as an automobile or the like, the spring 8 projecting rearwardly toward the steering knuckle connecting rod B, that is, the rod connecting the steering knuckles C of the front wheels. The clamp 9 is applied to the steering rod B at such a position that the spring 8 will 100 extend through the eye 15 without being bent when the wheels of the automobile are positioned so that the car will run straight ahead.

Whenever the steering rod B is shifted toward the right or left by the driver of the car, the eye 15 or guide will likewise be shifted, thus causing the spring 8 to be bent into substantially S-shape and put under tension, so that when the car has made the 110

turn or after pressure is released from the wheel thereof, the steering rod B will be returned to its normal position, that is, in such a position that the wheels of the car 5 will cause the latter to travel straight ahead. At each bend of the spring, the convolutions on the outer side of the curve separate as seen in dotted lines in Fig. 1, and the coiled spring operating in this manner has no tendency to break regardless of the amount of 10 bending.

It will be seen that such an attachment 15 for automobiles will be very useful, as it will enable the vehicle to hold a straight course without assistance from the driver, and will prevent the steering rod from accidentally shifting should the driver take his hand from the steering wheel. It is of comparatively simple construction, and is made 20 adjustable so that it can be connected readily to various types of cars.

From the foregoing description, taken in connection with the accompanying drawings, the construction, use and operation of 25 the invention will be readily understood.

As numerous changes in form, proportion, and in the minor details of construction may be resorted to without departing from the spirit of this invention, it is to be understood that I do not wish to be limited 30 to the construction herein shown and described other than as claimed.

I claim:—

1. In combination with the front axle and 35 the steering knuckle connecting rod of an automobile; an anchor member secured to said axle, a guide eye secured to said rod opposite said anchor member, and a longi-

tudinally disposed coiled spring secured rigidly at one end to said anchor member 40 and having its other end received in said eye, the convolutions of said spring being adapted to spread to permit abrupt bending without breakage.

2. A steering attachment for automobiles 45 comprising an anchor member and means for securing it to the front axle, a guide eye and means for securing the same to the steering knuckle connecting rod, and a coiled spring rigidly secured at one end to said anchor member, the other end of said spring being receivable in said eye, the convolutions of said spring being adapted to spread to permit abrupt bending without breakage.

3. A steering attachment for automobiles 55 comprising a base plate, means for clamping it to the front axle, said plate having an integral vertically extending lug provided with an opening, a straight coiled spring having one end positioned in the opening of 60 said lug, a set screw threaded through said lug for securing said spring in place, a guide eye in which the other end of the spring is received, and means for securing said eye to the steering knuckle connecting 65 rod, the convolutions of said spring being adapted to spread to permit abrupt bending without breakage.

In testimony whereof I have hereunto set my hand in the presence of two subscribing 70 witnesses.

JOSEPH C. ZUMWALT.
